CLAIM

The ornamental design for a body worn exercise cushion, as shown and described.

DESCRIPTION

FIG. 1 is a perspective view of a body worn exercise cushion showing my new design therefor. The broken line drawing representing a partially clad figure is for purposes of illustration only and forms no part of my design;

FIG. 2 is a bottom plan view shown in a flattened position;

FIG. 3 is a rear elevational view;

FIG. 4 is a left side elevational view, the right side elevational view being a mirror image thereof;

FIG. 5 is a front elevational view; and,

FIG. 6 is a top plan view.
